UNITED STATES PATENT OFFICE.

EDWARD SAMUEL BOND, OF BIRMINGHAM, ENGLAND.

MACHINE FOR MAKING WIRE NETTING.

Application filed December 27, 1923, Serial No. 683,012, and in Great Britain July 20, 1923.

This invention comprises certain improvements in or relating to machines for making wire netting, and more particularly relates to machines of the type involving superposed upper and lower pairs of longitudinal slides, with a series of complementary pairs of semi-cylindrical segments intermediately disposed at intervals within semi-circular recesses in the contact faces of each pair of slides, each complementary pair of segments being adapted to be collectively revolved, by means of a sliding rack disposed within one of the longitudinal slides so as to gear with a divided pinion on the pair of segments, when the slides are in certain relative positions, to thereby twist the pair of wires passing through the respective segments for formation of the netting, whilst intermittently the segments are adapted to be moved longitudinally by the slides in known manner into new positions in which they again rotate in differently selected pairs, the arrangement being such that during the intermittent longitudinal movement of the segments by the slides, the segments do not rotate.

The invention has for its purpose the provision of means whereby, in case of the recesses of the longitudinal slides becoming worn out, the considerable expense of complete renewal of the slides may be avoided, and whereby the machine may be adapted for the production of wire nettings of various meshes without the necessity for entire removal of the slides and replacement by slides having recesses of different size and pitch.

According to the present invention, the longitudinal slides embody interchangeable face plates in which are provided the semi-circular recesses for the rotatable semi-cylindrical segments, said recesses being proportionate in pitch to the particular size of mesh to be produced, and being of a diameter adapted to accommodate the particular size of segment to be used. Advantageously the longitudinal slide is built up from separate metal bars, which may be of uniform or of different qualities.

In order that this invention may be clearly understood and readily carried into practice, reference may be had to the appended drawings, upon which:

Figure 1 is a fragmentary plan of an upper pair of the longitudinal slides having the present improvements applied.

Figure 2 is an end elevation of Figure 1, in section on the line 2—2.

Figure 3 is a plan of one of the longitudinal slides and its interchangeable face plate, 60 as shown in Figures 1 and 2.

Figure 4 is a sectional end elevation of a front longitudinal slide and its interchangeable face plate in a modified form.

In a convenient embodiment of the invention, the longitudinal slides, each of a substantially channel-shaped formation, and inwardly open to provide upper and lower sliding contact faces, have said sliding contact faces provided on a set of interchangeable face plates *a* detachably secured to the superposed inwardly projecting extremities of the channel-shaped body part, the plates being either in one continuous length or in sections of convenient length. Each interchangeable face plate *a* is of substantially L-shaped cross-section, so as to be accommodated within longitudinal recesses formed in the extremities of the body part, and to be detachably secured therein by means of 85 screwed studs *b* or the like. The semi-circular recesses *c* for accommodation of the semi-cylindrical segments *d* are provided vertically in the faces of these interchangeable face plates *a*, the various plates being graduated according to the mesh to be produced, that is to say, the semi-circular recesses being of uniform diameter and pitch in each particular set of plates, but being of larger or smaller diameter and pitch 90 in the other sets of plates of the interchangeable series. By this means the interchangeable face plates *a* may be fitted to existing longitudinal slides to replace plates having 95 worn out recesses *c* therein, thereby avoiding the inconvenience and expense of complete renewal of the slides. In a similar manner the interchangeable face plates *a* may be utilized to provide for different sizes of mesh, without the necessity for entire removal and replacement of the longitudinal slides. Thus a machine may be adapted to produce, say, six different meshes of netting by the use of two extra sets of interchangeable plates *a* in conjunction with sets of segments *d* or by having two different ranges 100 of longitudinal movement of the slides and segments, or an additional multiple of meshes by the use of further sets of interchangeable plates *a* and segments *d*.

The interchangeable face plates *a* may be of the same or different metal to the body

part of the slide, and said body part may either be of solid form, or of a built-up construction. In this latter case, as illustrated in Figures 1 to 3, the body part may comprise upper and lower web or flange bars *e* assembled in conjunction with a connecting base or intermediate bar *f*, the three bars having recessed joints *g* and being rigidly secured together by steel pins *h* riveted therethrough, the bars being either of the same or of different qualities, for example, the two web or flange bars *e* being of mild steel or cast iron, and the base or intermediate bar *f* being of cast steel to obtain greater rigidity.

i is the divided pinion on each pair of segments *d*, and *j* is the rack disposed preferably within the rear slide for driving engagement with the series of pinions. *k* is the coil-holding tube supported by one of the lower pairs of segments *d*, and from which wire is fed to the corresponding upper segment, the complementary segments *d* of the upper and lower pairs being fed with wire direct from the bobbin.

The individual slides of each pair may each be of the construction already described. But if desired, the front slide, in which an internal rack is not ordinarily provided, may be of a somewhat modified construction, as illustrated in Figure 4, in which the interchangeable face plates *a*¹ having the semi-circular recesses *c* are of rectangular cross-section, secured by bolts or studs *b*¹ on opposite sides of a central web *f*¹ projecting inwardly from the body part *e*¹ of

the slide, which may be of a plain channel formation.

What I claim as my invention, and desire to secure by Letters Patent is:—

In a machine of the type referred to, for making wire netting, the combination of a facially opposed pair of slides arranged for a parallel reciprocating movement in opposite longitudinal directions, a pair of longitudinally extending bearing plates embodied detachably in the opposed faces of the respective slides, said plates having longitudinally spaced pluralities of semi-circular bearing recesses disposed in opposed pairs in the contact faces thereof, and semicylindrical twisting segments disposed in rotatable pairs within the respective pairs of recesses so as to take their bearings within said detachable plates; the spacing of the plurality of recesses in each plate being proportionate to the particular size of mesh to be produced, the recesses being of a diameter adapted to accommodate the particular size of segment to be used, and the plates being interchangeable in relation to the permanent slides, to thereby provide for wear and avoid the expense of complete renewal of the slides, and to adapt the machine for the production of nettings of various meshes without the necessity for entire removal of the slides and replacement by slides having recesses of different size and pitch.

In witness whereof I have hereunto set my hand.

EDWARD SAMUEL BOND.
